(57) **CLAIM**

I claim the ornamental design for a mobile cabin bedroom module, as shown and described.

DESCRIPTION

FIG. 1 illustrates a perspective view of a mobile cabin bedroom module employing an ornamental design in accordance with the present invention;

FIG. 2 is a front side view of the mobile cabin bedroom module of FIG. 1;

FIG. 3 is a back side view of the mobile cabin bedroom module of FIG. 1;

FIG. 4 is a left side view of the mobile cabin bedroom module of FIG. 1;

FIG. 5 is a right side view of the mobile cabin bedroom module of FIG. 1;

FIG. 6 is a top side view of the mobile cabin bedroom module of FIG. 1; and,

FIG. 7 is a bottom side view of the mobile cabin bedroom module of FIG. 1.

The dash-dot lines in the drawings represent the bounds of the claimed design.

1 Claim, 7 Drawing Sheets
